[57] ABSTRACT

A power supply device for use in a superminiature tape recorder is disclosed. The device comprises a reference voltage generator circuit for generating an output therefrom in response to a reference voltage, a constant-current circuit for generating a constant current to obtain the reference voltage, a starting circuit for supplying a starting current to the constant current circuit and for branching a part of the starting current, and an electronic switch for causing flow of starting current therein so as to turn the constant-current circuit OFF.

FIG. 1
PRIOR ART

FIG. 2

POWER SUPPLY DEVICE

This application is a continuation of application Ser. No. 404,379, filed Aug. 2, 1982 abandoned, which in turn is a continuation of Ser. No. 273,427, filed June 15, 1981, abandoned.

BACKGROUND OF THE INVENTION

The present invention relates to a power supply device with an electronic switch particularly for use with a tape recorder.

Recently, tape recorders have been subminiaturized, the power supplies therefor also tend to be miniaturized as integrated circuits, and switches in the devices also become electronic switches instead of mechanical switches which occupy large spaces.

If a switch which is mechanically turned ON or OFF is used, however, a power supply source can completely be cut off at the time of OFF switching condition and electric power to be consumed can completely cut to zero. However if an electronic switch is used, it is difficult entirely to cut the power consumed to zero in the OFF switching condition. As often seen in subminiature tape recorders, if a battery having small capacity is used, it is impossible to ignore the problem that the lifetime of the battery is short.

FIG. 1 shows an embodiment of a conventional power supply device. In FIG. 1, a transistor Q₄ is connected as a diode, and forms a current mirror circuit together with a transistor Q₅ to obtain a reference voltage. Moreover, in order to keep the reference voltage unchanged even during fluctuation of the power supply voltage, there is provided a constant-current circuit composed of transistors Q₂, Q₃ and resistors R₁, R₂, R₃. This supply device also includes a differential amplifier circuit composed of transistors Q₁₀, Q₁₁, Q₈ and Q₉, and a current-mirror circuit composed of transistors Q₆, Q₇ and resistances R₄, R₅. The transistors Q₁₀ and Q₁₁ are active loads of the transistors Q₈ and Q₉. Moreover, reference Q₁₃ is a control transistor for supplying current to a load R_L, and reference Q₁₂ is a transistor for driving a control transistor Q₁₃. The resistors R₇ and R₈ are feedback resistors for determining the output voltage V_{out} supplied to the load R₁, which output voltage V_{out} is (1+R₇/R₈) times the reference voltage. Reference Q₁ is an MOS FET of N channel type for forming an electronic switch and has an opened drain of CMOS IC as an output in the inside thereof. This electronic switch Q₁ turns the whole power supply device ON and OFF by biasing the transistor Q₃ ON or OFF. That is, when the electronic switch Q₁ is ON, the transistor Q₃ is cut off and the transistor Q₂ is also cut off, and then transistors Q₄, Q₅, Q₆, Q₇ and the transistors Q₈, Q₉, Q₁₀, Q₁₁, Q₁₂, Q₁₃ are cut off, and then all the transistors are cut off. But, the switch Q₁ has a very small potential difference between drain and source thereof while ON, so that the switch Q₁ has a current of V_{EE}/R₁ at maximum flowing therein. It means that if V_{ee}=3V, R₁=30 kΩ, the whole power supply device cannot be turned OFF as a current of about 100 μA flows into the N channel MOS FET. When such electronic switch is used, fairly large power is consumed even in the OFF condition, so that there is a drawback that the lifetime of the battery is shortened. Besides, since a current of 100 μA flows into FET as the switch Q₁, a large FET having large capacity must be used, which is not desirable for minimizing a switch.

SUMMARY OF THE INVENTION

An object of the present invention is to eliminate the above described disadvantages of the conventional power supply device.

Another object of the present invention is to provide a power supply device with the use of an electronic switch which can mitigate by a large margin the electric power to be consumed in the OFF condition.

According to the present invention there is provided a power supply device comprising a reference voltage generator circuit for generating an output therefrom in response to a reference voltage, a constant-current circuit for generating a constant current to obtain the reference voltage, a starting circuit for supplying a starting current to the constant-current circuit and for branching a part of the starting current, and an electronic switch for flowing the starting current therein so as to make the constant-current circuit OFF condition. The electronic switch is AMOS FET.

BRIEF DESCRIPTION OF THE DRAWING

FIG. 1 is circuit diagram showing a construction of one embodiment of the conventional power supply device; and

FIG. 2 is a circuit diagram showing a construction of one embodiment of a power supply device according to the present invention.

DESCRIPTION OF THE PREFERRED EMBODIMENT

FIG. 2 shows an embodiment of a power supply device according to the present invention. In FIG. 2, transistors Q₃₁, Q₃₂, Q₃₃ resistors R₂₅, R₂₆, R₂₇, R₂₈ form a reference voltage generator circuit having high efficiency. This circuit is a famous band gap reference voltage source. Resistors R₂₉ and R₃₀ compose a series resistor circuit for dividing a reference voltage. Moreover, transistors Q₃₈, Q₃₉ are amplifier transistors and form a differential amplifier circuit. Transistors Q₃₆, Q₃₇ are active loads of the above amplifier circuit. Moreover, a transistor Q₄₁ is a control transistor for supplying a current to a load R_L, a transistor Q₄₀ is a driving transistor for driving the control transistor Q₄₁, and resistors R₃₁, R₃₂ are feedback resistors for determining an output voltage supplied to the load R_L.

Transistors Q₂₉, Q₃₄, Q₃₅, are pair transistors and a transistor Q₃₀ has an emitter area which is twice the above transistors Q₂₉, Q₃₄, Q₃₅. These transistors Q₂₉, Q₃₀, Q₃₄, Q₃₅, form a current mirror circuit and form a constant current source. The transistors Q₂₉ and Q₃₀ establish a constant-current circuit for generating a constant current to obtain a reference voltage together with transistors Q₂₇ and Q₂₈ and resistors R₂₂, R₂₃ and R₂₄. In this case, a current value of the circuit is $V_{T1,n}/2R_{24}$. (Here, $V_T=kT/q$, q is the charge of an electron, k is the Boltzmann constant and T is the absolute temperature.) It is a matter of course that this current value is determined by $V_{T1,n}/R_{24}$ when the emitter area of the transistor Q₃₀ becomes n.

The transistors Q₂₇ and Q₃₀ each have a collector connected to the base of the other and further formed by thyristor connection. Moreover, the transistor Q₂₈ does not serve as a gate and the transistor Q₂₉ serves as a gate. Therefore, when a current is supplied to the base of the transistor Q₂₉ from the outside, the thyristor consisting of the transistor Q₂₇ and Q₃₀ turns ON and

each emitter of the transistors Q₂₉ and Q₃₉ flows a current thereto by the positive feedback operation.

Transistors Q₂₅ and Q₂₆ and resistors R₂₁ and R₂₂ form a starting circuit. In this case the transistor Q₂₅ is always biased so that the transistor Q₂₆ produces an extremely small collector current flowing through the resistor R₂₂ thereby to supply a bias current to the transistors Q₂₇, Q₂₈, Q₂₉ and Q₃₀. In this case, the resistor R₂₄ is set to make an emitter current of the transistor Q₂₉ 100 μ A for example and the resistor R₂₂ about 5 k Ω thereby to produce a voltage drop about 0.5 V here. Then, the transistor Q₂₉ goes ON so that the transistor Q₂₆ is completely cut off, thereby preventing the constant-current circuit consisting of the transistors Q₂₉, Q₃₀, Q₃₄ and Q₃₅ from the undesirable influence of a collector current of the transistor Q₂₆.

A transistor Q₂₄ is an N-channel opened drain MOS FET serving as an electronic switch.

With the above construction, if the switch Q₂₄ is turned OFF, the transistors Q₂₉, Q₃₀, Q₃₄ and Q₃₅ go ON, and the transistors Q₃₈, Q₃₉, Q₃₆, Q₃₇, Q₄₀ and Q₄₁ also go ON. Therefor, the power supply source goes ON to supply the load R_L. In this case, the switch Q₂₄ has an output impedance of several 10 M μ in the OFF state, so that the internal connection of the switch Q₂₄ can be ignored.

Next, when the switch Q₂₄ is turned ON, a starting current supplied to the constant-current circuit flows into the drain source electrodes of switch Q₂₄, so that the transistors Q₂₉, Q₃₀, Q₃₄, and Q₃₅ are cut off, and the transistors Q₃₈, Q₃₉, Q₃₆, Q₃₇ and Q₄₀ are cut off, and then the whole power supply source is placed in the OFF condition, and the output thereof to the load R_L is interrupted. In this case, if the resistor R₂₁ is made about 3 M μ , when the power supply voltage V_{EE} is 3 V, the current flowing into the resistor R₂₁ becomes about 1 μ A, so that if the transistors Q₂₅ and Q₂₆ are also made pair-like, the current flowing into the switch Q₂₄ is minimized to 100 nA. That is, as compared with the conventional ones, the power to be consumed in the switch can be mitigated by a large margin and the switch, i.e., FET having small capacity can be used, so that more minimization for the device can be obtained. Moreover, the current to be consumed at the time of switching off condition, as apparent from the above, is determined by a resistance value of the resistor R₂₁, but as an embodiment, it can be suppressed to 1 μ A even

with the use of an IC of 150 elements. Moreover, if FET is connencted to the resistor R₂₁ in series, the power to be consumed at the time of switching off condition can further be minimized. With the use of such circuit, when the power supply source is turned ON condition by turning the switch Q₂₄ OFF, the positive feedback operation is also performed by the transistors Q₂₇, Q₂₈, Q₂₉ and Q₃₀, so that the rising operation of the power supply source is advantageously quick.

With such construction, therefore, the power to be consumed at the time of switching the electronic switch OFF condition can be mitigated by a large margin, so that even in case of a battery having small capacity, a lifetime of the battery can sufficiently be secured, and the electronic switch itself can be miniaturized, and thus the present invention can contribute to miniaturize tape recorder or the like.

In addition, the present invention is not limited to the above embodiments but can be modified without departing from the scope of the invention.

As described above, according to the present invention, it is possible to provide a power supply device with the use of an electronic switch which can mitigate electric power to be consumed at the time of switching off condition by a large margin.

What is claimed is:

1. In a power supply device having a reference voltage generator circuit for generating an output therefrom in response to a reference voltage, the improvement comprising a constant-current circuit for generating a constant current to obtain the reference voltage, a starting circuit for supplying a starting current to the constant-current circuit and for branching a part of the starting current, and an electronic switch for shunting the starting current so as to turn the constant-current circuit OFF, said starting circuit and said constant-current circuit having active elements and passive resistive elements, said switch having only active elements and being connected only to active elements of said constant-current circuit and said starting circuit.

2. A power supply device as claimed in claim 1, wherein the electronic switch is an MOS FET.

3. A device as in claim 1, wherein said constant-current circuit includes an input having a transistor base and emitter said switch including an FET having source and drain connected directly to the base emitter.
